UNITED STATES PATENT OFFICE.

HERBERT O. CRIPPEN, OF LOUISVILLE, KENTUCKY.

SPIKE-HOLDER.

941,621.

Specification of Letters Patent. Patented Nov. 30, 1909.

Application filed February 23, 1909. Serial No. 479,463.

To all whom it may concern:

Be it known that I, HERBERT O. CRIPPEN, a citizen of the United States, residing at Louisville, in the county of Jefferson and State of Kentucky, have invented certain new and useful Improvements in Spike-Holders, of which the following is a specification.

This invention comprehends certain new and useful improvements in track equipment for railways, and the invention has for its object an improved spike holder which is adapted to be applied to the rail in a peculiar manner, and is arranged to extend across the head of a spike in order to effectually maintain the same against any loosening movement, the holder also serving as a shield to prevent the elements from entering the tie through the opening made by the spike, as is likely to result in the tie becoming rotted.

A further object of the invention is an improved spike holder which is susceptible of use in connection with the ordinary rails and the wooden ties in general use, and which may be applied to a track that has been already laid without the necessity of disturbing the same, the holder being also adapted to be quickly attached to the rail, and being retained positively in position thereon and requiring no subsequent attention, thus effecting a material economy in the cost of construction and maintenance of the track.

A still further object of the invention is a holder of this character which is constructed of an integral strip of sheet metal and consists essentially of a clip for embracing the base flange of the rail, and for engaging the spike, the clip being formed with a tension plate arranged to snap under the head of the rail to prevent the accidental displacement of the holder, and at the same time brace the rail.

With these and other objects in view that will more fully appear as the description proceeds, the invention consists in certain constructions and arrangements of the parts that I shall hereinafter fully describe, and then point out the novel features thereof in the appended claims.

For a full understanding of the invention and the merits thereof, and to acquire a knowledge of the details of construction, reference is to be had to the following de-

scription and accompanying drawing, in which:

Figure 1 is a sectional perspective view illustrating the application of my improved spike holder; Fig. 2 is a transverse section thereof; Fig. 3 is a similar view illustrating the manner of placing the holder in position; Fig. 4 is a perspective view of another embodiment of the invention; and, Fig. 5 is an enlarged fragmentary view thereof.

Corresponding and like parts are referred to in the following description and indicated in all the views of the drawing by the same reference characters.

My improved spike holder or keeper is preferably constructed of an integral sheet of suitable spring metal which is doubled upon itself at an intermediate point in order to constitute a clip 1. The clip consists of upper and lower spaced members 2 and 3 that are connected by a side plate 4. When the keeper is applied to a rail 5, as illustrated in Fig. 1, the lower member 3 is interposed between the base flange 6 of the rail and the upper face of the tie 7, the said lower member being preferably slotted, as indicated at 8, in order to embrace the spike 9. Inasmuch as the lower member 3 is adapted to embrace the spike, it will be observed that the holder is effectually prevented from creeping or moving longitudinally of the rail. The upper member 2 extends across and bears upon the head of the spike, and is relatively longer than the other member, so as to extend across the upper surface of the base flange, as shown. When in position, the extremity of the upper member is arranged in close proximity to the web 10. 11 designates a tension plate which is integral with the extremity of the upper member and is angularly disposed relative thereto and projects upwardly and is adapted to be snapped under the head 12 of the rail, the tension plate then extending along the corresponding side of the web 10 and serving to brace the rail to a greater or less extent.

It will be obvious that in order to insure of the holder being retained in position, it is necessary to provide positive means for preventing the lateral displacement thereof. For this purpose, the side plate 4 is preferably provided with an attaching ear 13 that outstands therefrom and is disposed in a plane preferably oblique to the plane of

the lower member 3. This ear extends across the upper face of the tie and is fastened thereto through the instrumentality of a screw 14 or like fastening element.

5 In the practical use of a holder constructed in accordance with my invention, the latter is placed in position, after the spike has been driven into the tie in engagement with the base flange of the rail. The 10 lower member 3 is then inserted between the base flange and the upper face of the tie, so that the clip 1 embraces the base flange and extends across the head of the spike. It is to be understood, however, that when 15 pushing the holder laterally into position in this manner, the tension plate 11 is disposed in such position that its upper end bears against the head of the rail, so that the tension plate is sprung or bent by such lateral movement. The screw 14 is then inserted 20 through the attaching ear 13 and embedded in the tie to maintain the keeper against lateral displacement. The parts then assume the position illustrated in dotted lines 25 in Fig. 3, with the upper member 2 in spaced relation to the base flange of the rail. In order to complete the attachment of the holder, it is merely necessary to take a suitable instrument and press downwardly 30 and inwardly upon the uppermost member 2 at the junction of the same with the tension plate 11, so as to admit of the tension plate clearing the head 12 and snapping into position beneath the same and against 35 the web 10.

By virtue of the arrangement of parts above described, it will be apparent that the tension plate braces the clip so as to assist in maintaining the spike against loosening 40 movement as well as retaining the keeper in place against removal. Should occasion require that the holder be detached from the rail, as in event of changing the gage of the track or the like, such may be quickly and 45 conveniently accomplished by removing the fastening element 14, whereupon the holder may be moved laterally sufficiently to disengage the lower member 3 from beneath the base flange of the rail, and thus entirely 50 release the holder.

In another embodiment of the invention, as illustrated in Fig. 4, the attaching ear 13 of the side plate is omitted, and the keeper is held against lateral displacement through 55 the instrumentality of an angle bar 15 that is formed with spaced openings 16 to admit of its attachment to the tie in such a manner as to serve as a stop against which the side plate abuts.

60 From the foregoing description, in connection with the accompanying drawing, it will be apparent that I have provided an improved spike holder which not only retains the spike against loosening movement, 65 but also constitutes a housing or shield to

prevent the elements from entering the tie through the opening made by the spike. Attention is also particularly directed to the fact that the keeper may be stamped from a blank of spring material so as to be susceptible of being easily and cheaply manufactured so as to be placed upon the market at a price not too great to prevent its general adoption. 70

Having thus described the invention, what 75 I claim is:—

1. A spike holder embodying a spring member extending over the base flange of the rail and yieldable downwardly to bear forcibly against the head of the spike, and 80 means for holding said member under stress.

2. As a new article of manufacture, a spike holder constructed of spring metal and consisting of a clip embodying spaced members, one of said members being slotted, 85 and a tension plate disposed angularly at the extremity of the other member and extending away from the slotted member, for the purpose specified.

3. As a new article of manufacture, a 90 spike holder comprising a clip consisting of spaced members and a plate connecting the same and formed with an outstanding attaching ear, one of the members being slotted, and a tension plate angularly disposed at the extremity of the other member and extending away from the slotted member, for the purpose specified. 95

4. A spike holder adapted to have one of its opposite ends take under the rail base 100 and its other end engage the head of the rail, and arranged intermediate of its ends to extend over the head of the spike.

5. A spike holder comprising a clip adapted to embrace the base flange of the rail and 105 extend over the head of the spike, and means carried by the clip for engaging the head of the rail.

6. A spike holder comprising a clip adapted to embrace the base flange of the rail and 110 extend over the head of the spike, and engaging means carried by the clip and adapted to snap under the head of the rail.

7. A spike holder comprising a clip adapted to embrace the base flange of the rail and 115 extend over the head of the spike, and a tension plate carried by the clip and designed to snap under the head of the rail.

8. A spike holder comprising a clip adapted to embrace the base flange of the rail and 120 extend over the head of the spike, engaging means carried by the clip and adapted to snap under the head of the rail, and means for holding the clip against lateral displacement.

9. A spike holder comprising a clip adapted to embrace the base flange of the rail and extend over the head of the spike, means carried by the clip for engaging the head of the rail, and an attaching ear also carried by 130

the clip and designed to be fastened to the tie to maintain the holder against lateral displacement.

10. A spike holder comprising a clip adapted to take under the base flange of the rail and embodying a member arranged to extend over the head of the spike, and a tension plate carried by and integral with said member and designed to snap into engagement with the head of the rail.

11. A spike holder embodying a member extending over the head of the spike, means for attaching said member to the tie, and engaging means carried by the member and adapted to snap under the head of the rail.

12. A spike holder embodying a spring member extending over the base flange of the rail and yieldable downwardly to bear against the head of the spike, means for at-

taching the member on one side of the spike, 20 and means disposed on the opposite side of the spike for holding the member under stress.

13. A spike holder embodying a spring member extending over the base flange of 25 the rail and yieldable downwardly to bear against the head of the spike, attaching means for securing one end of the member to the tie, and means disposed at the opposite end of the member for coöperating with 30 the rail to maintain the member under stress.

In testimony whereof I affix my signature in presence of two witnesses.
